CHARLES H. THOMAS, OF PHILADELPHIA, PENNSYLVANIA.

Letters Patent No. 65,842, dated June 18, 1867.

IMPROVED METHOD OF BOTTLING MINERAL WATERS.

The Schedule referred to in these Letters Patent and making part of the same.

TO ALL WHOM IT MAY CONCERN:

Be it known that I, C. H. THOMAS, of Philadelphia, in the county of Philadelphia, and State of Pennsylvania, have invented certain new and useful improvements in Bottling Mineral Waters under pressure; and I do hereby declare that the following is a full, clear, and exact description thereof, reference being had to the accompanying drawings, making part of this specification, and to the letters of reference marked thereon, like letters indicating like parts wherever they occur. To enable others skilled in the art to construct and use my invention, I will proceed to describe it.

My invention consists in bottling water from mineral springs under pressure, so as to retain the largest possible amount of gas in the water, and at the same time prevent it from coming in contact with the atmosphere. The drawings represent several plans of accomplishing this result, and also a plan for more thoroughly impregnating the water with gas, as hereinafter explained.

As is well known, the virtue of water obtained from mineral springs or wells consists principally in the gases contained in the water, together with the chemical matter held in solution. When exposed to the action of the atmosphere the gases escape, and the chemicals held in solution are separated and form a deposit at the bottom, giving to the water a filthy and disagreeable appearance, and greatly impairing its medicinal qualities. Hence it is an object to bottle it without permitting it to come in contact with the atmosphere.

It is also well known that the amount of gas held in solution by the water is in proportion to the pressure on the water and its temperature, that the amount of gas contained in the water increases in proportion to the depth from the surface, and also in proportion to the coldness of the water, and that hence it is an object to draw the water for bottling from the greatest possible depth in the well, and where it is the coldest. It is also an object to draw and bottle the water under the greatest possible amount of pressure, for the reason that in proportion as the pressure is removed the gas expands and decreases in quantity in proportion to the bulk of the water contained in a given space, and also escapes more readily therefrom.

In Figure 1, A represents a mineral well or spring into which I insert a tube, b, having its lower open end reaching to near the bottom. P represents a pit dug in the earth to some depth below the surface, into which the upper portion of tube b enters as represented, the tube being provided with a stop-cock and a nozzle to fit the mouth of bottles. It will be obvious that when water is drawn through the tube b it will be drawn direct from the bottom of the well, and under a hydrostatic pressure equal to the height of the water in the well above the discharge point of tube b. By lowering the pit the pressure may be increased to any desired extent, wherever the formation of the ground renders this method practicable. In order to break up the globules of gas, and more intimately mingle it with the water, I secure a finely-perforated diaphragm, a, made of porcelain, glass, or other non-corrosive material, in or near the bottom of the well, as represented in the drawings.

Figure 2 represents the same plan, with an arrangement for adding to the pressure on the water. In this case, A represents the well with the supply pipe inserted as before, and extending up and connecting with a cask E, there being a force-pump, f, applied at any suitable point to the pipe b, for forcing the water from the well up into the vessel E, which is supplied with a pipe and cock h for filling bottles therefrom. The vessel E is connected by a pipe, g, with another similar vessel, F, which latter is connected by a pipe, i, with a reservoir, R, placed at any desired height above the vessels E and F. By this arrangement it will be seen that water will be drawn from the lower part of the well, where it is cool, and highly charged with gas, and that it will flow from the cock h, under a hydrostatic pressure equal or due to the height of the fluid in the reservoir above the discharge pipe h. It is obvious that a discharge-cock may be applied to the pipe b in the pit P, and the water drawn therefrom, without or with the pressure of the column in the reservoir above.

In Figure 3 another modification of plan is shown. In this case no pit is used, the supply pipe b extending from near the bottom of the well, and connecting on the surface with a tank, T, of any desired height, there being a force-pump, f, applied at any suitable point to the pipe b, for forcing the water from the bottom of the well up into the tank T. C represents an air-chamber for causing a regular and continuous flow of the water into the tank, through the pipe b; and to prevent the air in the chamber C from coming into contact with the water as it passes through the chamber, I place within the chamber C a flexible lining or bag, e, the air in the chamber being outside of this bag or lining, which thus permits the air in the chamber to exert its full

pressure on the water, without coming in direct contact therewith. A tube with a cock, *n*, should be applied to the top of the tank to permit the escape of air therefrom, while being filled in the first instance. A discharge pipe, *l*, with suitable cocks and nozzles is applied to the bottom of the tank, for drawing the water into bottles or other vessels.

In many localities large quantities of the gas are constantly rising from the springs, or from the earth in their vicinity, and escaping into the atmosphere. For the purpose of utilizing this waste gas, I propose to build over the places where it escapes gasometers or receivers to catch and hold this gas, or in any other practicable manner to gather it into a suitable reservoir, from whence I force it by means of suitable pumps either into the tank from which the water is drawn, or into the bottom of the well, as represented in fig. 3, for the purpose of more strongly charging or impregnating the water with the gas. By a suitable arrangement the bottles themselves may be filled with the gas, so as to displace the air therefrom before filling them with the water. These various plans will be varied according to circumstances, the idea being in all cases to take the water from the lowest practicable point in the well, and to convey it into the receiving vessel under pressure, so as to retain the greatest possible amount of pressure, and to exclude it as far as possible from contact with the atmosphere.

Having thus described my invention, what I claim, is—

1. Bottling or drawing water from mineral wells or springs under pressure, substantially as described.
2. I claim taking the water from a point in the well or spring below the point of discharge, substantially as described.
3. I claim the use in a mineral well or spring of the perforated diaphragm *a*, as herein set forth.
4. I claim the charging of mineral waters with an extra supply of gas, either in the well or in the tank, substantially as herein described.

CHAS. H. THOMAS.
